UNITED STATES PATENT OFFICE.

THOMAS JEFFERSON MISSILDINE, OF ENTERPRISE, ALABAMA.

MOLD FOR EMBEDDING TABLETS IN CONCRETE.

No. 845,311.

Specification of Letters Patent.

Patented Feb. 26, 1907.

Application filed December 20, 1906. Serial No. 348,813.

To all whom it may concern:

Be it known that I, THOMAS JEFFERSON MISSILDINE, a citizen of the United States, residing at Enterprise, in the county of Coffee 5 and State of Alabama, have invented a certain new and useful Improvement in Molds for Embedding Tablets in Concrete; and I do hereby declare the following to be a full, clear, and exact description of the invention, such 10 as will enable others skilled in the art to which it appertains to make and use same, reference being had to the accompanying drawings, and to the letters and figures of reference marked thereon, which form a part of 15 this specification.

This invention relates to new and useful improvements in molds for embedding tablets in concrete, and consists in the provision of various details of construction and combinations and arrangements of parts which will be hereinafter fully described, and then specifically defined in the appended claims.

I illustrate my invention in the accompanying drawings, in which—

Figure 1 is a perspective view of my improved mold. Fig. 2 is a cross-sectional view through the mold, showing the manner of holding the tablet; and Fig. 3 is a sectional view through the tablet after the same has 30 been embedded in the concrete.

Reference now being had to the details of the drawings by letter, A designates the base of the mold, having standards B and a cross-piece C, connecting the latter.

Rising from the upper surface of the base are the cleats E parallel to each other, and pivotally mounted upon each cleat is a cam F.

H H designate two longitudinal strips of the mold-frame, having recesses H' in their 40 inner faces adapted to receive the cross-pieces K, forming the ends of the mold-frame. Said cams are adapted to be thrown against the outer faces of the longitudinal strips H, whereby the cross-pieces forming the ends of the frame may be held in said recesses while 45 the concrete is being molded therein.

Rising from the base of the mold is a raised table N of a smaller area than the tablet O, which is adapted to rest thereon and which is 50 designed to be embedded in a cement slab. The tablet projects a slight distance over the edges of the table, a sufficient distance to allow the cement or concrete to be forced underneath the same to securely hold the tablet 55 let to the slab when the latter is formed. A follower Q is placed upon the upper surface

of the tablet and is held clamped against the tablet by means of the screw R, which extends through an aperture in the cross-piece C, and by means of a nut S upon the screw 60 the latter may be forced down against the follower to securely hold the tablet in place while concrete is being poured into the mold for the purpose of anchoring the tablet to the slab. After the spaces underneath the overhanging edges of the tablet have been filled with the concrete or cement the follower is removed and the balance of the mold filled up with the concrete or cement, thereby making a solid slab with the tablet embedded 65 therein, and the face of the tablet will have a margin of cement extending about the entire periphery thereof, thereby forming a frame for the latter.

What I claim is—

1. An apparatus for embedding tablets in slabs of concrete, consisting of a mold, a table rising from the bottom thereof upon which the tablet rests, the edges of the tablet overhanging the edges of said table, and clamping means for holding the tablet upon the table while the space underneath the overhanging portion of the tablet is being filled in with concrete, as set forth.

2. An apparatus for molding tablets in concrete slabs, consisting of a table, a mold-bottom upon which said table is mounted, a frame made up of sections adapted to surround the table with a space intervening between the same, cams for holding the frame of the mold together, said table adapted to receive a tablet with the edges of the latter overhanging the table, a follower adapted to clamp the tablet upon said table while concrete is being filled underneath the overhanging edges thereof, as set forth.

3. An apparatus for molding tablets in concrete slabs, consisting of a table, a mold-bottom upon which said table is mounted, a frame made up of sections adapted to surround the table with a space intervening between the same, raised portions projecting from the bottom of the mold on the outside of said frame, and cam members pivotally mounted upon said raised portions and adapted to bear against the opposite sections of the frame to hold the same together, said table designed to receive a tablet with the marginal edges of the latter overhanging said table, a follower, and a screw bearing against the latter and adapted to hold the tablet upon the table while spaces underneath the

overhanging edges of the tablet are being filled with concrete, as set forth.

4. An apparatus for molding tablets in concrete slabs, consisting of a table, a mold-
5 bottom upon which said table is mounted, a frame made up of two sections having re-
cesses upon the inner faces thereof, end sec-
tions of the frame engaging said recesses,
clamping means for holding the end sections
10 in said recesses, said table adapted to receive
a tablet with the marginal edges of the same

overhanging the table, and means for holding the tablet upon the table while the spaces underneath the overhanging edges thereof are being filled with cement, as set forth.

15 In testimony whereof I hereunto affix my signature in the presence of two witnesses.

THOMAS JEFFERSON MISSILDINE.
